ENGINE STARTING MECHANISM

Francis Linder, East Orange, N. J., assignor to
 Eclipse Aviation Corporation, East Orange,
 N. J., a corporation of New Jersey

Application April 24, 1930, Serial No. 447,021

19 Claims. (Cl. 123—179)

This invention relates to apparatus for starting internal combustion engines, and more particularly to starting devices for use with installations embodying a plurality of engines.

5 One of the objects of the present invention is to provide means adapted for use in starting a plurality of internal combustion engines from a common control point in an efficient and reliable manner.

10 Another object is to provide novel starting means for a plurality of engines in which a single source of energy serves to actuate the starting mechanism of each of the engines selectively.

15 A further object is to provide novel means for readily, efficiently, and simultaneously connecting both a source of cranking energy and a source of electrical energy to any desired one of several engines to be started.

20 Another object is to provide control means for starting a plurality of engines which embody a novel distributor for both cranking energy and starting ignition current whereby any one of several engines may be selectively started from 25 a common control point.

25 A still further object is to provide a novel control system for starting a plurality of engines from a common point which includes a distributor for both cranking and starting ignition energy combined with a booster magneto which is actuated by a portion of the cranking energy.

30 Another object is to provide novel starting means for a plurality of engines wherein the cranking energy is used to actuate a booster magneto, and both the starting ignition current thus generated and the cranking energy are distributed selectively to the engines by a common control means.

35 These and other objects will appear more fully 40 in the detailed description of the invention which follows. Although only one embodiment of the invention has been described and illustrated in the accompanying drawings, it is to be expressly understood that these drawings are for the purposes of illustration only and are not to be construed as a limitation of the scope of the invention, reference being had for this purpose to the appended claims.

In the drawings:

45 Fig. 1 is a diagrammatic view of the invention applied to a multi-motored airplane;

50 Fig. 2 is a sectional view of the distributing unit constituting one element of the invention, the view being taken along line 2—2 of Fig. 3;

55 Fig. 3 is another sectional view of the distribut-

ing unit, the view being taken along the line 3—3 of Fig. 2;

Fig. 4 is a sectional view of the current generating unit and the actuating means therefor; and

Fig. 5 is a sectional view taken on line 5—5 of Fig. 4.

Fig. 6 is a diagrammatic view illustrating the entire system schematically.

Referring now to the drawings, wherein like reference characters indicate like parts throughout the several views, the embodiment of the present invention disclosed therein comprises, in general, a common distributor for both cranking energy and starting ignition current which may 15 selectively connect the sources of energy to any one of a plurality of engines to be started, and a booster magneto adapted to be actuated by a motor run by a portion of the cranking energy, and to have its output distributed to the proper 20 engine by means of the common distributor. For purposes of illustration, the preferred form of the invention has been shown as installed in an aeroplane having a plurality of engines, each of which is equipped with a starter and a main magneto, 25 the cranking energy and starting ignition current for which are distributed from the control means which may be situated in any location convenient to the operator, as in the cockpit.

As shown, the common distributor or control 30 means, designated generally at 4, which may be mounted in any suitable manner and location, as in the cockpit 5 of a multi-engine aeroplane 6, comprises a casing or casting 7, within which are housed a plurality of valves, passageways, and 35 valve operating mechanism constituting the means for distributing the cranking energy to the various engines, and an electrical distributor head 8, removably secured to the back of casting 7 in any desired manner, as by spring clips 9, for 40 distributing starting ignition current to the engine. As shown in Fig. 1, casting 7 is substantially triangular in cross section, but it is to be understood that this construction is dependent upon the number of engines with which the distributor is designed for use, and may thus take 45 any desired form.

Cranking energy, such as compressed air or other fluid under pressure, is supplied to distributor 4 from any suitable source, such as a 50 reservoir 10, through a supply pipe 10a, which has a threaded engagement with a boss 11 projecting from the center of one of the flat sides of casting 7, and is transmitted from the distributor to the respective starters 12 of a plurality of 55

engines 13 by means of pipes or tubing 14. Starting ignition current is supplied to distributor head 8 by a wire or cable 15 from a booster magneto 16 which is driven by a fluid pressure motor 17 in a manner later to be described, and is transmitted from the distributor to the respective main magneto 18 or engines 13 by suitable wiring 19. These individual starters and main magneto may be of any conventional design, as for example, that shown at 28 and 29, respectively, in Fig. 2 of Patent No. 1,124,736 issued to J. A. Heany on January 12th, 1915. When the Heany construction is employed, relation of the parts to the associated engine may, in each case, be similar to the arrangement shown in Fig. 2 of the Heany patent above referred to and reproduced in Fig. 6 of the drawings of the present application, wherein the parts 28 and 29 of Heany are designated by the reference characters 12 and 18, respectively; the parts 24, 53, 23, and 22 of Heany, by the reference characters 10, 10b, 88, and 89, respectively; and the parts 31, 32, 39, 41, B, and C of Heany, by the reference characters 91, 92, 93, 94, 95, 96, respectively, all of which parts will be further described herein-after or will be understood by reference to the description of the corresponding parts, and the functions thereof, in the Heany patent above referred to. It will be understood that all of the electrical connections of this starting system may be properly shielded in any approved manner.

Within the triangularly shaped casting 7 there are provided a plurality of supply passageways 20 which are parallel to the flat sides of the casting 35 and which intersect at the vertices of the triangle to form valve chambers 21. Supply pipe 10a communicates with one of these passageways 20, and thus connects them all directly to the source 10 of the compressed air or other cranking energy. Within the portion of casting 7 bounded by passageways 20 and chambers 21, and coaxial with the median lines of the triangle thus formed, are housed a plurality of distributing supply valves 22, seated against the inner surfaces of valve chambers 21 and normally held closed on said seats by means of coil springs 23, the pressure of which can be adjusted by cap nuts 24 which are threaded into casting 7 at its corners directly over valves 22.

Each valve 22 is provided with a valve stem 25, the end of which projects within a cylindrical bore 26 formed in casting 7 and is forced by the pressure of spring 23 into contact with the surface of a control cam 27 formed on an enlarged portion 28 of a distributor shaft 29, the latter being rotatably journaled in casting 7 by any suitable means such as a ball bearing 30 which is held within bore 26 between enlarged portions 28 of shaft 29 and an annular retaining plate 31 secured to said casting as by screws 32. Spring 23, together with the air pressure, is effective to hold valve 22 on its seat.

Control cam 27 is so shaped that in the position shown in Fig. 2 all of the valves remain closed, but when rotated from this neutral position, a high part 33 causes one of the valves to open while the other two remain closed. High part 33 of cam 27 is also provided with a small indentation 34 into which the end of valve stem 25 projects when the valve is fully opened, and which thus acts as a retaining or locking means preventing the accidental closing of the valve due to the air and spring pressure exerted thereon.

One end of shaft 29 projects from the face of

distributor 4 and is fitted with a suitable handle 35 pinned thereto as at 36, the angular position of which indicates the position of cam 27 and hence provides a means of selectively controlling the opening of distributing supply valves 22. If desired, the face of distributor 4 may be suitably marked so as to indicate which valve is open, according to the position of handle 35.

Just below each valve 22, coaxial with and surrounding valve stem 25, is formed a cylindrical chamber 37 from which there leads, at right angles thereto and parallel to shaft 29, a passageway 38 extending to the back of casting 7 and communicating there by means of a threaded nipple 39 and gland 40 with the pipe or tubing 14 leading to one of the starters 12.

Adjacent the inner end of nipple 39, which is threaded into the back of casting 7, passageway 38 is provided with an enlarged cylindrical portion 41 through which there passes, in a radial direction, a one-way valve housing 42. The main portion of valve housing 42 is substantially cylindrical in shape, but is provided with a diametrical bore or hole 43, and an axial bore or hole 44, which intersect to form a T-connection. Axial bore 44 extends to the inner end of housing 42 and is provided with a beveled seat 45 for a ball 46 which is held within bore 44 as by a pin 47, and is adapted to act as a one-way valve. Valve housing 42 is also provided with an integral stem 48 around which is placed an exteriorly threaded sleeve 49, the outer end of which has a squared-off countersunk head 50 within which the end of stem 48 is upset. There is thus formed a rigidly assembled structure which is threaded radially into casting 7 and securely held thereto by a lock nut 51 and washer 52, the lower portion of valve housing 42 fitting into a recess 53 with bore 44 registering with a radial passageway 54, and bore 43 registering with passageway 38.

Radial passageways 54, one for each one-way valve, terminate in an annular conduit 55, centrally located within casting 7, which is in turn connected by means of a radial passageway 56 and a supply pipe or tube 57, with the fluid pressure motor 17 which drives the booster magneto 16.

Fluid pressure motor 17 and magneto 16, the details of which form no part of the present invention, may be of any suitable construction, but are preferably designed to be compact, light in weight, and of a high speed variety in order to meet requirements for aircraft usage. As shown, motor 17 comprises a casing 58, elliptical in cross section as shown in Fig. 5, forming a motor chamber within which there is suitably journaled as in ball bearings 59, a cylindrical rotor 60. Slidably disposed in radial grooves 61 formed in rotor 60 are a plurality of vanes 62 which are always resiliently urged outward against the inner surface of casing 58 as by means of springs 63. At substantially diametrically opposite portions of casing 58 (on the shortest diameter thereof), longitudinal supply passages 64 are formed which communicate with supply pipe 57 and with each other by an annular conduit 65, and with the interior of casing 58 by inlet ports 66. A plurality of exhaust ports 67 are also provided connecting the interior of casing 58 with the atmosphere, the exhaust ports in each half of the elliptical motor chamber being spaced approximately 135 to 180 degrees from their inlet ports. It will thus be seen that any fluid under pressure which is supplied to motor 17 through pipe 75

57 will enter supply passages 64, pass through inlet ports 66 and enter the space between rotor 60 and casing 58, exert its pressure against vane 62 thus turning rotor 60, and be forced by the following vane 62 out to the atmosphere through exhaust port 61.

The rotation of rotor 60 is transmitted by means of a short coupling shaft 68 to the rotor 69 of booster magneto 16. This magneto is preferably of the usual inductor type wherein a plurality of rotating inductors 70 of magnetic material such as soft iron distribute and alternate a magnetic flux through a core 71 around which are wound primary and secondary coils 72 and 72a. The high tension current thus generated is supplied to a terminal 73 on the magneto from whence it is transmitted by a suitable wire or cable 15 to the distributor 4. It will be understood that the return lead from the booster magneto may be grounded or otherwise connected to the ignition system of each of the engines 13.

As hereinabove stated, the magneto 16 may be of any suitable construction known to the art and need not necessarily employ the specific details or inter-relation of parts above described, which details and inter-relation of parts are touched upon herein merely by way of illustration of a specific construction which may be adopted or dispensed with and replaced by any other suitable magneto or equivalent ignition device which persons skilled in the art may see fit to employ.

Referring again to the common distributor 4, distributor head 8, which may be made of any suitable insulating material, is provided with a central bore 14 and is so secured to the back of casting 1 that said bore is coaxial with distributor shaft 29. Housed in the outer end of said bore 14 is a metallic terminal member 75 with which wire 15 is electrically connected in any suitable manner, as by a snap tip 76 soldered thereto. Terminal 75 is also in electrical contact through a spring 77 with a rotary switch shaft 18 carrying a resilient switch arm 79 which is secured to shaft 29 for rotation therewith, whereby movement of handle 35 causes arm 79 to swing correspondingly into contact with any selected one of a plurality of terminals 80 radially disposed in the distributor head 8 around central bore 14, and each connected by suitable wiring 19 to the main magneto 18 of one of the engines 13. It is to be understood that there are the same number of terminals 80 as there are distributing supply valves 22, and that each terminal is disposed in the same radial plane with its corresponding valve.

Switch shaft 18 is drivably connected to but insulated from distributor shaft 29 in any suitable manner, as by means of a short coupling shaft 81 of insulating material having squared or flattened ends of reduced size which engage corresponding recesses formed in the adjacent ends of distributor shaft 29 and switch shaft 18, the central portion of coupling shaft 81 being of the same diameter as the shafts to be connected and serving as a separator to maintain them in their proper operative positions within the distributor. Coupling shaft 81 is also rotatably supported in an insulating diaphragm 82 interposed between the back of casting 1 and a flange 83 forming the base of distributor head 8, thus completely insulating the electrical distributing means from the remainder of the common distributor. The operative relation between switch shaft 18 and

distributor shaft 29 is such that switch arm 79 is co-planar with high part 33 of control cam 27 and control handle 35, thus providing for simultaneous connection of both cranking energy and starting ignition current to any selected engine by rotation of handle 35 to the desired position.

The operation of the above described apparatus is as follows: With the control handle 35 turned to its neutral or "off" position, cam 27 occupies the position shown in Fig. 1, and all distributing supply valves 22 are closed by the action of springs 23. Switch arm 79 also lies in a corresponding angular position, in contact with the inner insulating surface of distributor head 15 8 and out of contact with all terminals 80. If desired, a valve 10b may also be provided in supply pipe 10a to shut off from distributor 4 the supply of compressed air, or other fluid under pressure used as the cranking force when the starting system is not in use, thus avoiding possible loss of pressure by leakage.

When it is desired to start any selected one of engines 13, the valve 10b in supply pipe 10a is opened and control handle 35 and distributor shaft 29 rotated to the proper angular position wherein control cam 27 and switch arm 79 open the distributing supply valve 22 and make contact with the terminal 80, respectively, corresponding to the engine to be started. Compressed air, or other fluid under pressure, now flows from the reservoir 10 through supply pipe 10a and supply passageways 20 to valve chamber 21 of the open valve 22. Passing through the open valve the air enters chamber 37, leaves 35 through passageway 38, and through enlarged portion 41, nipple 39, and pipe or tubing 14 is supplied to the starter 12 where it may be utilized in any desired manner to crank the engine 13 being started. At the same time, a portion of the air entering enlarged portion 41 of passageway 38 passes through the one-way valve in housing 42 by means of diametrical bore 43 and axial bore 44, forcing ball 46 off its seat 45, if necessary, and entering annular conduit 55 through radial passageway 54. It will be understood that the air in conduit 55 is prevented from leaking through passageways 54 into the supply lines to the other starters not in use by means of the other one-way ball valve, balls 46 being forced against their seats 45 by the pressure of the air.

From annular conduit 55 the air is lead by means of radial passageway 56 and supply pipe 57 to the fluid pressure motor 17, which, in the manner previously described, is actuated by the fluid pressure and drives booster magneto 16 at a high rate of speed. The high tension ignition current thus generated is delivered by wire or cable 15 to terminal member 75 of distributor head 8, through spring 77 to switch shaft 18, and 60 through switch arm 79 to terminal 80, whence it is transmitted by wiring 19 to the main magneto 18 and ignition system of the engine 13 being started.

When the selected engine 13 has been started, 65 control handle 35 may be either returned to neutral and the starting system thus disconnected, or turned to another position for starting another engine.

In the event of leakage of air from reservoir 70 10 during the interval that the engine is not in operation, a pressure may be developed within reservoir 10 by means of an explosive firing mechanism 84 operatively associated with said reservoir, or one or more of the cylinders of the 7:

engine 13 may be utilized to compress air to be delivered to said reservoir 10 by way of a conduit 89 controlled by a valve 88 which may be of the type indicated at 23 in Fig. 2 of the Heany patent above referred to. Also as disclosed in the Heany patent, the establishment of a driving connection between the starter 12 and the crank-shaft of the engine may be effected electro-magnetically under the control of a switch 91 in a circuit fed by the magneto-generator 18, the said circuit being tapped from the main ignition circuit 93 which leads to the interrupter 94 and the primary winding of the induction coil 95, the secondary winding being adapted for delivery of high tension current to the cylinders 13 in succession, in accordance with the rotation of the distributor arm of the unit indicated at 96.

There is thus provided by the present invention, a novel starting system for internal combustion engines whereby a plurality of engines may be started from a common control point in an efficient and dependable manner. A novel distributor has been provided by the use of which the operator, from a central control point, may simultaneously connect both a source of cranking energy and a source of starting ignition current to any selected one of a plurality of engines. This invention requires the provision of only one source of cranking energy, such as a compressed air reservoir, and only one booster magneto, a common distributor serving to efficiently connect these sources of energy to the selected engine to be started, and thus greatly reduces the weight of the starting system, a particularly important consideration in multi-engine aircraft installation. By utilizing a portion of the cranking energy for actuating the booster magneto, another saving in weight and space is effected since it eliminates the need for batteries for running a motor for this purpose.

It will be obvious that the invention is not limited to the form shown in the drawings, but is capable of a variety of mechanical embodiments. For example, any suitable type of motor and booster magneto may be substituted for the structures shown and described. In certain instances it may be desirable to employ electrical energy rather than a fluid under pressure as shown in which event the distributing mechanism becomes a double electrical distributor rather than a combined air and electric distributor as illustrated. Also, it is obvious that the invention may be applied to groups of engines which are not installed in aircraft, and to groups which contain more or less than three engines, as shown. If desired, in large installations, the engines may be started in groups of two or more, instead of singly, and the invention is thus not limited to the specific form of distributor shown. Various other changes, which will now appear to those skilled in the art, may be made in the form, details of construction and arrangement of the parts without departing from the spirit of the invention, and reference is therefore to be had to the appended claims for a definition of the limits of the invention.

What is claimed is:

1. A starting system for a plurality of internal combustion engines comprising a fluid actuated starter for each engine, a main magneto for each engine, a single source of actuating fluid, a single source of starting ignition current, and means for selectively connecting both of said sources to the starter and magneto, respectively, of any selected one of said engines.

2. The combination with a power plant comprising a plurality of engines, of fluid actuated means for cranking each engine, a single source of actuating fluid, a main magneto for each engine, a single booster magneto, and a common distributor for simultaneously connecting both the source of actuating fluid and the output of the booster magneto to the cranking means and main magneto, respectively, of any selected one of the plurality of engines. 10

3. The combination with a power plant comprising a plurality of engines, a fluid pressure starter and a main magneto for each engine, of a single source of fluid under pressure, a single booster magneto, and a common distributor under control of the operator for simultaneously connecting both said source of fluid under pressure and said booster magneto to the starter and main magneto, respectively, of any selected one of the plurality of engines. 15

4. In apparatus for starting a plurality of engines, a fluid pressure starter for each engine, a single source of fluid under pressure, a main magneto for each engine, a single source of starting ignition current, and a single operating instrumentality for selectively connecting both of said sources to the starter and main magneto, respectively, of any one of said engines for starting the same, said single source of starting ignition current comprising a booster magneto and a fluid pressure motor for actuating the same. 20

5. In apparatus for starting a plurality of engines, a fluid pressure starter for each engine, a single source of fluid under pressure, a main magneto for each engine, a single source of starting ignition current, said source comprising a booster magneto and a fluid pressure motor for actuating the same, and a distributor for selectively connecting both of said sources to the starter and main magneto, respectively, of any one of said engines for starting the same, said distributor being adapted to connect the source of fluid under pressure to said fluid pressure motor simultaneously with its connection to any one of the fluid pressure starters. 45

6. In apparatus for starting a plurality of engines, the combination of a booster magneto, a fluid pressure motor for actuating said magneto, a source of fluid under pressure, and a distributor for selectively connecting the output of said magneto to any one of the plurality of engines, said distributor including means for connecting the source of fluid under pressure to said fluid pressure motor at the same time that it connects said magneto to an engine. 50

7. In apparatus for starting a plurality of engines, the combination of a magneto, a fluid pressure motor for actuating said magneto, a fluid pressure starter for each engine, a source of fluid under pressure, and a distributor for selectively connecting said source of fluid under pressure to the starter of any desired one of said plurality of engines, said distributor also including means for connecting said source of fluid under pressure to said fluid pressure motor simultaneously with its connection to any one of said starters. 60

8. In a power plant having a plurality of engines, means for selectively starting said engines from a common control point comprising a single source of actuating fluid, a single source of starting ignition current, and a distributor for simultaneously connecting both of said sources to any desired one of said plurality of engines for the purpose of starting the same. 70

9. In apparatus for starting a plurality of en- 75

5 engines, a booster magneto, a single source of fluid under pressure, a distributor having an electrical inlet and a fluid inlet to which said magneto and said source of fluid under pressure are respectively connected, and a plurality of pairs of outlets connected to said engines, each pair of outlets comprising an electrical outlet and a fluid outlet, and means for simultaneously connecting both of said inlets to any selected pair of said outlets.

10. In apparatus of the class described, a single source of fluid under pressure, a magneto, a fluid pressure motor for actuating said magneto, a distributor having inlets connected to 15 said source and said magneto and having a plurality of pairs of outlets, each pair consisting of a fluid outlet and an electrical outlet, and control means for selectively connecting said source with any desired one of said fluid outlets and 20 said magneto with the electrical outlet paired therewith, and simultaneously connecting said source with the fluid pressure motor.

11. In apparatus of the class described, a distributor having an electrical inlet, a fluid inlet, a 25 plurality of pairs of outlets, each pair consisting of an electrical outlet and a fluid outlet, an additional single fluid outlet, common control means for selectively connecting both of said inlets to any desired pair of said outlets, and simultaneously connecting said fluid inlet to said 30 additional single fluid outlet, a generator for supplying current to said electrical inlet, a fluid motor for driving said generator and a fluid supply line connecting said last named outlet with 35 said motor.

12. In apparatus for starting a plurality of engines from a common control point, a distributor comprising a single fluid inlet, a plurality of fluid outlets, a plurality of valves each controlling 40 communication between the fluid inlet and one of said fluid outlets, an electrical inlet terminal, a plurality of electrical outlet terminals, a switch for connecting the inlet terminal to any one of said outlet terminals, and common control means for selectively opening any desired one of said valves and simultaneously rotating said switch to connect the inlet terminal with an 45 outlet terminal.

13. In apparatus for starting a plurality of engines from a common control point, a distributor comprising a single fluid inlet, a plurality of fluid outlets, a plurality of valves each controlling communication between the fluid inlet and one of 50 said fluid outlets, an electrical inlet terminal, a plurality of electrical outlet terminals, a switch for connecting the inlet terminal to any one of said outlet terminals, common control means for selectively opening any desired one of said valves and simultaneously rotating said switch to connect the inlet terminal with an outlet terminal, a generator for supplying current to said electrical inlet terminal, a fluid motor for driving said generator, and means responsive to actuation of said common control means for establishing communication between said fluid inlet and said fluid motor when any one of said valves 55 is opened.

14. A starting system for a plurality of engines comprising a fluid pressure starter for each 60 engine, a main magneto for each engine, a single source of fluid under pressure, a single booster magneto, and a common control means for simultaneously connecting said source of fluid pressure and said booster magneto to the starter 65 and main magneto, respectively, of any selected

75 engine, said common control means comprising a distributor having a fluid inlet connected to said source of fluid under pressure, a plurality of fluid outlets connected to said starters, a plurality of valves each controlling communication 80 between said fluid inlet and one of said fluid outlets, an electrical inlet connected to said booster magneto, a plurality of electrical outlets connected to said main magnetos, a switch connecting said electrical inlet to said electrical outlets, 85 and manually operable control means for selectively opening any one of said valves and simultaneously connecting said electrical inlet to one of said electrical outlets.

15. A starting system for a plurality of engines 90 comprising a fluid pressure starter for each engine, a main magneto for each engine, a single booster magneto, a fluid pressure motor for actuating said magneto, a distributor having a fluid inlet 95 connected to said source of fluid under pressure, a plurality of fluid outlets connected to said starters, a plurality of valves each controlling communication between said fluid inlet and one of said fluid outlets, an electrical inlet connected to said booster magneto, a plurality of electrical outlets connected to said main magnetos, a switch connecting said electrical inlet to said electrical outlets, 100 an additional single fluid outlet connected to said fluid pressure motor, manually operable 105 control means for selectively opening any one of said valves and simultaneously connecting said electrical inlet to one of said electrical outlets, and at the same time providing communication between said fluid inlet and said additional 110 single fluid outlet when any one of said valves is opened.

16. A starting system for a plurality of internal combustion engines each of which employs electrical ignition energy to produce the power developing combustion comprising a fluid actuated cranking device for each engine, a single source of actuating fluid for all of said cranking devices, a single circuit controlling the electrical ignition energy for all of said engines, and a common control unit for operatively connecting said single source and said single circuit with any one of 120 said engines, at will.

17. In apparatus of the class described, a distributor having an electrical inlet, a fluid inlet, 130 a plurality of pairs of outlets, each pair consisting of an electrical outlet and a fluid outlet, a generator for supplying current to said electrical inlet, a fluid motor for driving said generator current, and common control means for selectively connecting both of said inlets in any desired pair of said outlets and simultaneously establishing communication between said fluid inlet and said fluid motor.

18. A system of control for an internal combustion engine of the type which requires ignition current for starting purposes, the combination with said engine of a current generator, a fluid motor for driving said current generator, a source of actuating fluid for said motor, a normal ignition unit associated with said engine for supplying ignition current thereto during normal operation of the engine, and a single common instrumentality for electrically connecting said generator with said normal ignition unit of said engine and at the same time establishing communication between said fluid source and said fluid motor.

19. A system of control for a plurality of internal combustion engines of the type which require 140

ignition current for starting purposes, and also embody a unit for supplying ignition current during normal operation, the combination with said engine of current generator and a fluid motor for driving said current generator, a source of actuating fluid for said motor, and a single com-

mon instrumentality for electrically connecting said generator with the normal ignition unit of any one of said engines and at the same time establishing communication between said fluid source and said fluid motor.

FRANCIS LINDER.
